UNITED STATES PATENT OFFICE.

MARCUS L. DAY, OF POLSON, MONTANA.

PIPE-FASTENER.

1,099,846.

Specification of Letters Patent.

Patented June 9, 1914.

Application filed June 12, 1912. Serial No. 703,315.

To all whom it may concern:

Be it known that I, MARCUS L. DAY, a citizen of the United States, residing at Polson, in the county of Flathead and State of Montana, have invented new and useful Improvements in Pipe-Fasteners, of which the following is a specification.

The present invention relates to pipe sustaining devices for the flues of chimneys.

In carrying out my invention it is my purpose to provide simple and effective means which are adapted to be employed in the construction of an ordinary brick chimney and which are further adapted to support and maintain within the flue opening of the chimney the smoke pipe of an ordinary stove.

I also aim to provide a device of this character which shall be simple in construction, cheap to manufacture, and readily positioned so as to not interfere with the laying of the bricks comprising the chimney but which will also form reinforcements for the chimney.

It is also my purpose to provide a pipe fastener which shall be sustained between the courses of brick directly above and below the flue opening, the said fastener preferably comprising a pair of elements, each being formed from a single strand of wire, and each of the said strands having a portion which projects beyond the chimney breast, and which is provided with an eye for the reception of the straightened ends 35 of pipe engaging loops. The portion of each of the members, which may be termed the body thereof, embodies spaced connected arms, the rear portion of which being arranged at a right angle to the said body, the 40 space between the rightangular portion and the body providing for the reception of the mortar employed in the construction of the chimney breast, and the said mortar effectively sustaining the fasteners immovably 45 upon the said chimney breast.

With the foregoing objects in view, the invention further consists in the novel construction, combination and arrangement of parts set forth in and falling within the 50 scope of the appended claim.

In the drawing, Figure 1 is a sectional view of a chimney showing my device applied thereon. Fig. 2 is a perspective view of one of the stove pipe sustaining 55 members, the dotted lines indicating one of

the bricks of the chimney which is arranged over the said sustaining member.

In the drawing, 1 designates a chimney of brick construction, and 2 the stove pipe opening therein.

3-3 indicate, what I term, the tie members which are adapted to be arranged between the bricks that provide the walls of the opening 2. Each of these members 3 comprises an elongated arm 4 which has its free end bent to provide an eye 5, while its opposite end is bent at an angle to the member 4 and provides a substantially U-shaped member 6, the end of which is continued in a plane with but at a suitable distance from the arm 4, and provides what I term the shorter arm 7 of the device. This arm has its extremity bent angularly toward the arm 4, and the said angular portion is looped around the said arm 4, as indicated by the 75 numeral 8.

As illustrated in the drawing, the tie members are permanently secured between the bricks which form the wall of a chimney, about the flue opening and are located on opposite sides of the said opening. The arms 4 and 7 are disposed longitudinally between two of the bricks while their U-shaped members 6 are disposed vertically or in a line with the inner end or side of the bricks 85 forming the walls of the opening 2, the said tie receiving the mortar which connects the bricks.

The elongated arms 4 project a suitable distance beyond the chimney, and their eyes 90 5 are adapted to receive the ends of a wire member 9 which has its central portion looped around the horizontal portion or that portion of a stove pipe 10 which enters the opening 6. The eye of the lower member 4 95 also receives the end of a wire member 9', the said wire being looped around and secured to the vertical portion of the pipe 10.

Having thus described the invention, what I claim is:

A pipe fastener for chimneys consisting of tie members permanently secured between the courses of brick which form the wall of the chimney about a flue opening and located on opposite sides of said opening, each of said members formed of a piece of wire and comprising an elongated arm projecting beyond the chimney wall and having an eye at its outer end, the inner end of the said arm being bent up at an angle to form a 110

loop and then extended to form a short arm parallel with and spaced from the elongated arm and then bent toward the longer arm and secured thereto, a stove pipe having its 5 elbow projecting into the flue opening, a wire loop member secured to the horizontal portion of the pipe projecting into the flue opening, and the loop member having extensions secured to the eyes of the tie arms, 10 and a wire loop member secured to the ver-

tical portion of the stove pipe and having an extension secured to the eye of one of the tie arms.

In testimony whereof I affix my signature in presence of two witnesses.

MARCUS L. DAY.
